UNITED STATES PATENT OFFICE.

LOUIS LOWENSTEIN AND SIMON ROBBINS, OF NEW YORK, N. Y.

HAND-BAG AND LIKE ARTICLE.

1,220,761.

Specification of Letters Patent. Patented Mar. 27, 1917.

Application filed October 19, 1916. Serial No. 126,475.

To all whom it may concern:

Be it known that we, LOUIS LOWENSTEIN, a citizen of the United States, and a resident of the city of New York, borough of Manhattan, in the county and State of New York, and SIMON ROBBINS, a citizen of the United States, and a resident of the city of New York, borough of the Bronx, in the county of Bronx and State of New York, have invented new and useful Improvements in Hand-Bags and like Articles, of which the following is a full, clear, and exact description.

The object of the invention is to provide certain new and useful improvements in hand bags, satchels, purses and like articles, whereby the time and labor required for fastening the bag body in position in the framework is reduced to a minimum and at the same time the bag body is securely fastened in position in the frame and without danger of any portion of the bag pulling out or becoming detached.

In order to accomplish the desired result, use is made of wires extending along the raw edges of the bag body, and means for fastening to the bag body the said wires and their fastening means fitting into channels of the usual frame, and retaining means for holding the wires in position in the frame.

A practical embodiment of the invention is represented in the accompanying drawings forming a part of this specification, in which similar characters of reference indicate corresponding parts in all the views.

Figure 1 is a face view of the improvements as applied to a hand bag;

Fig. 2 is a perspective view of a portion of the hand bag in open position and showing more particularly the rivets used for fastening the bag body in position in the frame members; and

Fig. 3 is an enlarged sectional plan view of one of the frame members and the corresponding side of the bag body, the section being on the line 3—3 of Fig. 1.

In the manufacture of hand bags and similar articles as now generally practised, considerable time and highly skilled labor is required in order to accurately, neatly and securely insert and fasten the raw edges of the flexible bag material in position in the frame members throughout the entire extent of the same with a view to prevent any portion of the edges from pulling out of the channel of the frame members during the time the bag is in use. In order to permit of assembling the bag and the frame without the employment of skilled labor and at the same time securely and neatly hold the bag in position in the frame is the object of the invention presently described in detail.

The hand bag in its general construction consists of a bag body 10 consisting of leather, fabrics or other flexible material, and a frame 11 to which the bag body 10 is attached, the frame being formed of two members 12 pivotally connected with each other by pivots 13 to allow of opening and closing the hand bag or similar article in the usual manner. The frame members 12 are of channel or U-shaped construction in cross section, as plainly shown in Fig. 3, and in order to fasten the edges of the bag body 10 and its lining, if such is used, in position in the frame members, the following arrangement is made: A wire 14 bent to conform to the shape of the frame member 12 is extended along the raw edge of the corresponding front or back of the bag body 10, and this wire is fastened to the bag body 10 by suitable means, preferably stitches 15, passing around the wire and through the margins of the bag body 10, in the manner of over-stitching on a suitable sewing machine. The wires 14 with the stitches 15 and the marginal portions of the front and back of the bag body 10 are pushed into the channels of the frame members 12, and then rivets 16 or other retaining devices are used for fastening the bag body securely in place in the frame members. The rivets 16 extend transversely through the sides of the channelled frame members and through the marginal portions of the bag material adjacent the stitches and the wires 14 so that the bag body is not liable to become detached from the frame members at any point throughout the extent thereof. It is understood that as the wires 14 fit into the frame members, and the margins of the front and back of the bag material of the bag body 10 are fastened together throughout the length of each wire, it is evident that no one portion of the bag material can pull out of the corresponding frame member 12. The stitches may be continued along the edges of the front and back of the bag body 10 at the joints thereof and as indicated at 17 in Fig. 2, to prevent the raw edges of the bag body

material from showing at the pivot ends of the frame 11.

It will be noticed that the wires can be readily fastened by the stitches to the edges 5 of the front and back of the bag body 10 by the use of suitable sewing machines, and the bag body prepared in this manner can be readily pushed into position in the members 12 of the frame 11 without requiring much 10 time or skilled labor. After this has been done, the rivets 16 can be readily driven in place by the use of a suitable riveting machine.

The wires 14 may be round, oval or polygonal 15 in cross section and hence we do not limit ourselves to the particular shape of the cross section of the wire.

Having thus described our invention, we 20 claim as new and desire to secure by Letters Patent:-

1. In hand-bags and similar articles, a frame formed of channeled members, a bag body of flexible material, wires bent to conform to the shape of the channeled members, 25 the wires extending along the edges of the front and back of the bag body, fastening means for securing the wires to the edges of the bag body throughout the length of the wires, the wires and fastening means fitting 30 into the channels of the said frame members, and retaining devices extending through the sides of the channeled members for holding the wires in position in the channels of said members.

2. In a hand bag and similar article, a frame formed of channeled members pivotally connected with each other to open and close, a bag body, wires conforming to the shape of the said frame members and extending along the raw edges of the said bag 40

body, and stitches passing around the wires and through the margins of the bag body to fasten the wires in place on the bag body, the said wires and stitches fitting into the channels of the said frame members, and retaining means for permanently fastening the said bag body in place in the frame members. 45

3. In a hand bag and similar article, a frame formed of channeled members pivotally connected with each other to open and close, a bag body, wires conforming to the shape of the said frame members and extending along the raw edges of the said bag body and stitches passing around the wires 55 and through the margins of the bag body to fasten the wires in place on the bag body, the said wires and stitches fitting into the channels of the said frame members, and rivets on the said frame members and extending through the bag body at the margins thereof to securely fasten the bag body in position in the frame members. 60

4. In hand bags and similar articles, a frame formed of channeled members, a bag body of flexible material, wires conforming to the shape of the frame members, the wires extending along the marginal edges of the bag body and secured thereto throughout the length of the wires, the edges of the bag 65 body with the wires and securing means fitting into the channels of the said frame members, and retaining means for the wires extending through the sides of the frame members and the marginal portion of the bag material at the inner sides of the said wires. 70
